SHOULDER SHAPED DRESS AND SUIT HANGER

Fred K. Dobana, New York, N. Y.

Application June 26, 1947, Serial No. 757,241

1 Claim. (Cl. 223—88)

1

This invention relates to a shoulder shaped dress and suit hanger.

It is an object of the present invention to provide a hanger which is shaped at the ends to properly secure the padded shoulders of dresses or coats without getting the shoulder of the dress or suit out of shape.

Another object of the present invention is to provide with such a hanger having an enlarged end for adequately supporting shoulders, a means for supporting a skirt or trousers thereunder centrally of the enlarged shoulder support whereby the suit or dress part will be retained in spaced relationship from the skirt or trousers supported thereunder.

Other objects of the present invention are to make a shoulder shaped dress and suit hanger which is of simple construction, inexpensive to manufacture and efficient in operation.

For other objects and for a better understanding of the invention, reference may be had to the following detailed description taken in connection with the accompanying drawing, in which

Fig. 1 is a side elevational view showing one form of the invention with the enlarged shoulder support at the opposite ends of the same and with an inturned recess at the opposite sides for receiving the opposite side edges of a skirt.

Fig. 2 is a top plan view of the coat hanger shown in Fig. 1.

Fig. 3 is a cross-sectional view taken on line 3—3 of Fig. 1.

Fig. 4 is a side elevational view of a modified form of the invention wherein a bar is disposed under the shoulder support for the purpose of supporting trousers thereon.

Fig. 5 is a transverse cross-sectional view taken on line 5—5 of Fig. 4.

Referring now particularly to Figs. 1 to 3, 10 represents the main body portion of the hanger on which there is formed a hook formation 11 by the means of which the hanger is supported on a rod or hook within a closet. On opposite ends of the hanger are wide shoulder supports 12 which are wider at the ends than inwardly thereof and which taper while curving upwardly from the ends toward the hook formation of the hanger. The inner portions of the support formation 12 overlie inwardly curved recesses 13 having at the lower side of the same projections 14. Into this recess the top of a skirt can be folded or projected and the skirt will be rested upon the projection 14. The shoulder supports are not

2

only curved longitudinally but are curved transversely so that the front and rear edges lie below the top of the support portion.

In Figs. 4 and 5, there is shown a hanger which 5 has a horizontal rod portion 17 for receiving trousers. This rod portion is integral with the main part of the hanger and depends from end portions 18 integrally connected with the part 19. The rod portion 17 and its depending portions 18 10 underlie the shoulder support portion 12.

While various changes may be made in the detail construction, it shall be understood that such changes shall be within the spirit and scope of the present invention as defined by the appended claim.

I claim:

A shoulder shaped dress and suit hanger comprising a substantially thin main body part with a hook formation extending upwardly therefrom, 20 shoulder support portions of a greater overall dimension than said main body part extending from the main body part on opposite sides thereof which are adapted to support the shoulders of a dress or suit so as to maintain the shape of same, said shoulder support portions being wide at their outer ends and tapering inwardly toward the main body part, said shoulder portions being further curved transversely of the same, said body part having upper and lower outwardly 25 directed portions defining inwardly directed garment receiving recesses therebetween into which the top of a skirt can be extended, projections on said lower portions extending into the recesses and adapted to engage the top of the skirt to 30 retain the skirt therein, and said recesses lying beneath the inner ends of the tapered shoulder portions.

FRED K. DOBANA.
